US00D831204S

(12) **United States Design Patent** (10) **Patent No.:** **US D831,204 S**
(45) **Date of Patent:** **** Oct. 16, 2018**

(54) **ENTERAL SYRINGE**

(71) Applicant: **NEOMED, INC.**, Woodstock, GA (US)

(72) Inventors: **Benjamin M. Davis**, Woodstock, GA (US); **Aaron N. Ingram**, Canton, GA (US); **Mark M. Costello**, Co. Mayo (IE); **John Burke**, County Roscommon (IE)

(73) Assignee: **NEOMED, INC.**, Woodstock, GA (US)

(**) Term: **15 Years**

(21) Appl. No.: **29/533,134**

(22) Filed: **Jul. 14, 2015**

Related U.S. Application Data

(63) Continuation-in-part of application No. 29/530,724, filed on Jun. 18, 2015, which is a continuation-in-part of application No. 29/519,107, filed on Mar. 2, 2015, now Pat. No. Des. 807,502.

(51) **LOC (11) Cl.** **24-02**

(52) **U.S. Cl.**

USPC **D24/130**

(57) **CLAIM**

The ornamental design for an enteral syringe, substantially as shown and described.

DESCRIPTION

FIG. 1 is a perspective view of an enteral syringe showing our new design.

FIG. 2 is a front elevation view thereof.

FIG. 3 is a rear elevation view thereof.

FIG. 4 is a first side elevation view thereof.

FIG. 5 is a second side elevation view thereof.

FIG. 6 is a first end elevation view thereof; and,

FIG. 7 is a second end elevation view thereof.

The broken lines show portions of the design that form no part of the claimed.

1 Claim, 4 Drawing Sheets

US D831,204 S
